(57) CLAIM

The ornamental design for a combination power adapter and detachable battery, substantially as shown and described.

DESCRIPTION

FIG. 1 is a front, top perspective view of a combination power adapter and detachable battery comprising an embodiment of a new, original and ornamental design;

FIG. 2 is a front view thereof;

FIG. 3 is a back view thereof;

FIG. 4 is a left-hand side view thereof;

FIG. 5 is a right-hand side view thereof;

FIG. 6 is a top view thereof;

FIG. 7 is a bottom view thereof; and,

FIG. 8 is another front view of the combination power adapter and detachable battery of FIG. 1 with the battery detached from the power adapter.

The broken line portions of the figure drawings are included to show unclaimed subject matter only and form no part of the claimed design.

1 Claim, 5 Drawing Sheets
